CAR CONSTRUCTION

Edward H. Wells, Jr., New York, N. Y., assignor to
Johns-Manville Corporation, New York, N. Y.,
a corporation of New York

Application February 16, 1940, Serial No. 319,191

7 Claims. (Cl. 105—423)

The present invention relates to improvements in railway cars and the like, and particularly to insulated passenger cars.

At present, most passenger cars include a layer of insulation between the outer wall sheathing and an interior liner. A conventional construction comprises a metal frame including longitudinal and transverse members interposed between and supporting the outer sheathing, suitably welded or riveted metal plates, and the inner liner of plywood, composition material, or the like. Blankets or pads of felted mineral wool or other suitable insulating material are placed in the spaces defined between the sheathing and liner.

It has been found that a considerable amount of moisture is at times present within the wall spaces, the moisture soaking into the insulation and greatly impairing its insulating efficiency. The moisture also causes unsightly moist spots on the inner liner, as well as contributing to the rusting out of the metal parts. It has been determined that the presence of this moisture may be due in part to opening of the seams of the metal sheathing, permitting leaks to occur during adverse weather conditions. For the most part, however, the water is the result of the condensation of vapor within the car wall. Thus, particularly where the exterior temperatures are low, as in cold winter weather, and the interior of the car is maintained at the temperature and relative humidity required for the comfort and health of the occupants of the car, the interior air contains a relatively large amount of water vapor. The inner liner, being comparatively porous, permits the vapor to pass therethrough to the wall spaces containing the insulation, where it condenses within or substantially within the insulation adjacent the cold outer sheathing, the temperature of which is substantially below the dew point of the moisture vapor. As a result, the deleterious effects, previously referred to, occur.

The primary object of the instant invention is the elimination of the above-referred to objectional conditions within the wall of a railway car or the like. The term "wall" as used herein includes the roof and floor wall, as well as the side wall.

Another object of the invention is the provision of means to space the insulation from the outer sheathing to permit circulation of air adjacent the sheathing to reduce condensation, and to permit drainage of moisture which may accumulate on the sheathing.

A further object of the invention is the provision of continuous passageways in the walls of the car leading to the exterior thereof to permit the removal of water which may gather in the wall, as well as to allow circulation of outside air through the wall.

Another object of the invention is the provision of positive means to circulate outside air through the passageways referred to above.

10 A still further object of the invention is to provide a car wall structure as described above, including means to eliminate or substantially retard the movement of moisture vapor from the interior of the car to the wall space.

15 My invention will be more fully understood and further objects and advantages thereof will become apparent when reference is made to the more detailed description thereof which is to follow and to the accompanying drawing, in which:

20 Fig. 1 is a sectional view of a portion of a railway car wall construction embodying the invention;

Fig. 2 is a sectional view taken on the line 2—2 of Fig. 1;

25 Fig. 3 is a sectional view taken on the line 3—3 of Fig. 1;

Fig. 4 is a view similar to Fig. 2, depicting a modification of the invention; and

30 Fig. 5 is a sectional view similar to Fig. 3, depicting another modification of the invention.

Referring now to the drawing, and particularly to Fig. 1, there is shown a car wall construction of generally conventional type comprising vertical frame members or posts 10 (see Fig. 2) and horizontal frame members 12. Carried by the frame is an outer sheathing 14, suitably comprising metal plates secured by welding, riveting, or the like, to the frame. The sheathing extends completely over the side and roof of the car and includes a bottom plate 16 extending beneath the car floor. The frame also supports an inner liner 18 which may be formed of plywood, composition materials, metal, or the like. The liner includes floor 20. The sheathing 14, forming the outer roof of the car, may be reinforced as by purlins or stiffening members 26. It will be understood that the above description relating to conventional elements is of an exemplary nature only and is not to be considered as limiting the invention inasmuch as any suitable car wall structure may be employed.

Located within the wall spaces defined by the sheathing 14 and liner 18 and also between the floor 20 and bottom plate 16 is thermal-insulating material 22, preferably comprising batts or

blankets of mineral wool or other fibrous material. The batts are confined by the longitudinal and vertical frame members and extend the entire length and width of the space divisions defined thereby to provide a substantially continuous layer of insulation. The insulating batts or blankets suitably carry an outer facing layer 24 comprising asbestos felt or the like which is inherently moisture-pervious.

In accordance with the instant invention, passage of moisture vapor through the more or less pervious liner 18 and floor 20 is reduced by the provision of a substantially vapor-proof barrier 30 comprising, for example, asbestos or other paper heavily impregnated with an asphalt or similar waterproofing medium. The vapor barrier 30 may be secured to the insulating batts by an adhesive or the like or may be a separate element placed between the batts and the liner 18.

Also in accordance with the invention, the insulating batts are spaced from the outer sheathing 14 as by wires or metal strips 32 extending longitudinally of the car wall and suitably carried by the vertical frame members 10. The wires or strips 32 may extend only between adjacent vertical frame members 10 and be secured thereto by welding or the like or may pass through perforations in the vertical frame members and extend the length of or substantially the length of the car. In the latter case the perforations in the frame members 10 for the reception of the wires are located substantially in the neutral axis of the frame members, with the result that no substantial weakening of the structure results.

The horizontal or longitudinal frame members 12, and the purlins 26 as well, are provided with perforations 34 at suitable intervals to permit movement of air and moisture therethrough, the perforations aligning with the spaces between the insulation and the outer sheathing. The lower end member 35 of the wall and plate 16 are provided with perforations 36 opening to the exterior of the car.

In the above described construction, the vapor barrier 30 inhibits to a substantial extent the passage of moisture from the heavily moisture-laden air within the car to the wall spaces. However, such moisture vapor as does pass therethrough and condenses on the inner surface of the sheathing 14, and also water which may leak within the wall, is permitted to run down the wall, passing through the perforations 34 in the horizontal members and finally through perforations 36 at the lower end of the wall, with the result that no substantial amount of water comes in contact with the insulation blanket. Hence, the insulation does not soak up the moisture with the deleterious effects previously referred to, nor does the moisture gather in the bottom of the wall, as has previously been found to be the case, with consequent rusting of the metal parts. Furthermore, the presence of the openings 36 and perforations 34 permits a substantial circulation of air throughout the wall spaces between the insulation and sheathing, with the result that a large proportion of the moisture vapor is removed from the wall without condensing, and also water which may leak into the wall is vaporized and similarly removed.

In accordance with a further feature of the invention, forced circulation of air through the wall spaces may be provided to remove moisture vapor therefrom. For this purpose, there is

showed, by way of example, in Fig. 1 conduit 50 having one or more branches 52 communicating with the space between the insulation and outer sheathing. The conduit is connected to the output side of an air pump (not shown), and which may be placed at any suitable location, which forces exterior air into the space, the air circulating therethrough and finally escaping from exit ports, as for example, the openings 6. In this way, a positive flow of exterior air is assured whereby moisture-laden air is rapidly removed and any water present in the wall is evaporated. In lieu of a pump, the forward motion of the car may be utilized to provide the air circulation, the conduit 50 being connected in this case to any air scoop or the like at the front end of the car. Alternatively to forcing air through the space in the manner above described, the conduit may be connected to the exhaust side of the pump or other air withdrawing means to draw exterior air through openings 36 and to circulate the same through the wall spaces.

Referring now particularly to Fig. 4, the construction shown is that previously described, except that in place of the wires or straps 32, an open-mesh structure 40 such as expanded metal, woven wire mesh, or the like is employed. The woven mesh or expanded metal can be suitably secured in position, as, for example, by welding to the frame members.

In the installation of the insulation in accordance with the invention, suitably after the outer sheathing is secured over the frame structure and the wires 32 or foraminous mesh 40 is in place, the insulating batts or blankets 22 are pressed into the space divisions defined by the framing members and against the retaining means 32 or 40. In the side walls, clips 42 may be employed to hold the insulation in place. In the car roof, preferably extending wires 44 are used for this purpose, the wires being secured to the transverse framing members. In the event that the vapor barrier 30 is a separate element from the insulating batt, this is then applied and the inner liner 18 secured in a conventional manner to the framing members.

It will be noted that in Fig. 1 the wires or straps 32 have been employed in the roof of the car, as well as the side walls. However, if desired, their function may be performed by the stiffening members or purlins 26 and the wires eliminated in this portion of the car.

As an alternative to supporting the insulation by the wires or expanded metal or the like and installing the same in the manner above described, the insulating pads or batts 22 may be secured to the panels forming the interior liner 18 as by an adhesive or mechanical means 60, such as wire fasteners or the like (see Fig. 5). The batts 22 are secured to the liner or panels prior to installation of the latter, preferably with a vapor barrier 30 between the batt and liner, and the batts are located on the panels to fit in between the longitudinal and vertical framing members. The batts being of less thickness than the width of the wall space, a channel is provided between their outer side and the sheathing.

Having thus described my invention in rather full detail, it will be understood that these details need not be strictly adhered to, but that various changes and modifications will suggest themselves to one skilled in the art, all falling within the scope of the invention as defined by the subjoined claims.

What I claim is:

1. A wall structure for railway passenger cars and the like comprising an outer substantially air-impervious sheathing, a substantially continuous inner liner spaced from said sheathing, and defining with said outer sheathing a space closed from the interior of the car, framing members within said space supporting said sheathing and liner, vapor-permeable insulating units within said space and located between said framing members, means at spaced intervals supporting said insulating units against said liner to provide a passageway between said insulating units and sheathing, and means located at spaced points opening said space to communication with the exterior of the car.

2. A wall structure for railway passenger cars and the like comprising an outer substantially air-impervious sheathing, a substantially continuous inner liner spaced from said sheathing, and defining with said outer sheathing a space closed from the interior of the car, framing means including longitudinally extending members within said space supporting said sheathing and liner, vapor-permeable insulating units disposed within said space and located between said framing members, a vapor barrier comprising a substantially moisture-proof membrane between said insulating units and said liner, means at spaced intervals supporting said insulating units away from said sheathing to define a passageway between the insulating units and sheathing, and means located at spaced points in said wall opening said passageway to communication with the exterior of the car.

3. A railway passenger car or the like comprising a wall including an outer substantially air-impervious sheathing, a substantially continuous inner liner spaced therefrom and defining with said outer sheathing a space closed from the interior of said car and extending from one side to the other of the car, framing means including longitudinal members and members at substantially right angles thereto dividing said space and supporting said sheathing and liner, vapor-permeable insulating units disposed within said space and located between said framing members and supported at intervals to define spaces between the units and sheathing, a vapor barrier comprising a substantially moisture-impervious membrane between said insulating units and liner, openings in said longitudinal members, and drainage and ventilating openings at the base of the wall at both sides of the car.

4. A railway passenger car or the like comprising a wall including an outer weather-resistant, substantially air-impervious sheathing, a substantially continuous inner liner spaced from said sheathing and defining with said outer sheathing a space closed from the interior of said car, framing means including longitudinal and vertical members dividing said space and sup-

porting said sheathing and liner, vapor-permeable insulating units within said space and located between said members, spaced longitudinally extending elements carried by said vertical members spacing said insulating units from said sheathing, openings in said longitudinal members, ventilating openings in communication with the space at the upper part of the wall, and drainage and ventilating openings in communication with the space at the base of the wall said openings leading to the exterior of the car.

5. A railway passenger car or the like comprising a wall including an outer weather-resistant sheathing, a substantially continuous inner liner spaced from said sheathing and defining with said outer sheathing a space closed from the interior of said car, framing means including longitudinal and transverse members dividing said space and supporting said sheathing and liner, vapor-permeable insulating units within said space and located between said framing members, foraminous means carried by said framing members spacing said insulating units from said sheathing, openings in said longitudinal members, ventilating openings in communication with the space in the upper part of the wall, and drainage and ventilating openings in communication with the space at the base of the wall said openings leading to the exterior of the wall.

6. A railway passenger car wall comprising an outer sheathing, longitudinal framing members and framing members at right angles thereto supporting said sheathing, insulating units located between said framing members, and longitudinally extending wires passing through said second-mentioned framing members at substantially the neutral axis thereof and maintaining said insulating units in spaced relationship to said sheathing.

7. A wall structure for railway passenger cars and the like comprising an outer sheathing, a substantially continuous inner liner spaced from said sheathing and defining with said outer sheathing a space closed from the interior of said car, horizontal and vertical framing members within said space supporting said sheathing and liner, vapor-permeable insulating units within said space and located between said framing members, means spacing said insulating units from said sheathing to provide substantially continuous spaces between the insulating units and sheathing, openings extending through said horizontal members, an opening in said outer sheathing adjacent the base of the wall, and an opening in communication with the upper part of the wall, said openings leading to the exterior of the car, and means for forcing exterior air into said spaces to circulate the air therethrough and exhaust the same from said spaces through said openings.

EDWARD H. WELLS, JR.
